United States Patent Office

Des. 196,462
Patented Oct. 1, 1963

196,462

ROOF VENTILATOR

Louis J. Jenn and James W. Schwier, Indianapolis, Ind.,
assignors to Jenn-Air Products Company, Inc., Indianapolis, Ind., a corporation of Indiana

Filed Jan. 7, 1963, Ser. No. 73,065

Term of patent 14 years

(Cl. D62—3)

Fig. 1.

Fig. 2.

Fig. 3.

FIG. 1 is a side view of a roof ventilator embodying our new design.

FIG. 2 is a side perspective view thereof.

FIG. 3 is a top perspective view thereof.

The undisclosed sides of the roof ventilator are identical to the two sides shown.

We claim:

The ornamental design for a roof ventilator, as shown and described.
